Orange, N. J., a corporation of New Jersey

Application March 29, 1939, Serial No. 264,774

34 Claims. (Cl. 82—1.1)

This invention relates to machines for resurfacing phonograph records, and more particularly to improvements in such machines for facilitating their use. While the invention has particular utility, and is shown and described in connection with a machine for resurfacing records of the type primarily used in connection with commercial phonographs or dictating machines, no unnecessary limitation thereto is intended.

10 In some respects this invention has certain features in common with those disclosed in my co-pending application Serial No. 280,902, filed June 24, 1939, and entitled "Phonograph record resurfacing machines" and in a copending application 15 of George H. Fritzinger, Serial No. 246,304, filed December 17, 1938, and entitled "Phonograph record resurfacing machines," which application is connected by common ownership with the present application.

20 Phonograph record resurfacing machines of the type above mentioned comprise a rotatable record support, usually in the form of a mandrel, a carriage movable along the mandrel, a controllable driving means for rotating the mandrel, 25 and moving or feeding the carriage, and a resurfacing tool mounted on the carriage and settable into operative position relative to a record on the mandrel. The operation of resurfacing a record involves the performance of a series 30 of primary operations comprising a mounting of the record on the machine, a setting of the tool into operative position, a starting of the driving means to cause rotation of the mandrel and a feeding of the carriage along the mandrel in a 35 direction operative to cause a refacing, or a cutting away of a surface layer, of the record, a stopping of the driving means, and then a removal of the record from the machine. These primary operations may each involve several sub-operations, 40 all of which are to be performed in certain sequence in the proper use of the machine.

45 It is an object of my invention to provide a phonograph record resurfacing machine in which the various operations in the resurfacing of a record are largely automatically performed and controlled.

It is another object of my invention to provide a machine for resurfacing phonograph records which is highly simple in the control of its operation and moreover well-nigh foolproof against mis-operation.

It is another object of my invention to provide new and improved control means for a resurfacing machine.

55 It is another object of my invention to provide

such new and improved means in a phonograph record resurfacing machine as will render the machine essentially automatic in the performance of all operations required in a record resurfacing except for a change of record on the machine.

It is another object of my invention to provide means by which the machine is put into operation, as an incident to the mounting of a record on the machine, to cause a resurfacing of the record so mounted.

It is a further object of my invention to provide, in a phonograph record resurfacing machine, means rendered effective as an incident to a single manipulation on the machine to perform all operations pertaining to a record resurfacing except for a change of record on the machine. It is a feature of my invention to cause the tool-carriage to be reciprocated across the record, from and to a start position, for each 20 resurfacing of a record, the tool being, however, operative only during the last half cycle of each tool-carriage reciprocation.

It is another object of my invention to provide a feeding means for reciprocating the tool-carriage across the record from and to a start position at predetermined and different rates of speed.

It is another object of my invention to automatically set the resurfacing tool into operative 30 position at the completion of the first half cycle of each tool-carriage reciprocation.

It is another object of my invention to provide power operated means for setting the resurfacing tool.

It is another object to provide a driving means which is so controlled that when the same is placed in operation it causes one reciprocation of the tool-carriage across the mandrel against and in a direction of normal record resurfacing movement.

Another object of my invention is to cause the mandrel to be rotated only during the movement of the tool-carriage in the direction of its record resurfacing movement.

It is another object of my invention to provide a phonograph record resurfacing machine which is so arranged and controlled that upon the performance of a simple manipulation thereon a 50 cycle of operations is effected to cause a resurfacing of a record on the machine and then a restoration of the machine into a normal inoperative condition for re-operation at will.

Other and allied objects will more fully appear 55

from the following description and the appended claims.

In the description of my invention reference is had to the following drawings, of which:

5 Figure 1 is a top plan view, partly in section, of a phonograph record resurfacing machine incorporating my invention, the various parts of the machine being shown in the positions they assume during the progress of the tool-carriage

10 through its record resurfacing movement, the direction of which is indicated by the arrow shown;

Figure 2 is a right-hand side elevational view of the mechanism of Figure 1;

15 Figure 3 is an enlarged right-hand, fragmentary view, partly in section, of the mechanism of Figure 1;

20 Figure 4 is a fractional view of the tool-setting means partly in section on line 4—4 of Figure 3, showing the relative positions assumed by the tool-setting means when the tool is set in operative position;

Figure 5 is a fractional sectional view of the tool-setting means taken along line 5—5 of Figure 2;

25 Figure 6 is a top plan view, partly broken away, of the rear right-hand portion of the machine showing mechanism automatically operated at the completion of the first half cycle of each carriage reciprocation for placing the machine in condition to produce a resurfacing of the record;

Figure 7 is a fractional vertical cross-sectional view taken along the line 7—7 of Figure 6;

30 Figure 8 is a right-hand view, taken on line 8—8 of Figure 1 and partly broken away, showing an automatic clutch for coupling the driving means of the machine to the mandrel;

Figure 9 is a diagrammatic view of the control circuit for the machine;

35 Figure 10 is a fractional front elevational view, partly in section, showing principally the aforementioned automatic conditioning mechanism for the machine;

Figure 11 is a sectional view on line 11—11 of Figure 10;

40 Figure 12 is a right-hand elevational view of mechanism, controlled by the endgate latch, for starting the machine, the base plate of the machine appearing in cross-section substantially along the line 12—12 of Figure 1; and

50 Figure 13 is a fractional horizontal sectional view taken substantially along the line 13—13 of Figure 12.

Reference being had to the figures, particularly Figures 1 and 2, there will be seen a phonograph record resurfacing machine incorporating my invention and comprising a base plate 1 having a flange 1' extending downwardly from the rim thereof and provided with a left-hand upright standard 2, right-hand upright standards 3 and 4, and an intermediate upright standard 5. In the right-hand portion of the base plate adjacent to the standard 4 there is an upright boss 6 on which there is pivoted, by a screw 7, an endgate 8 biased into open position by a torsional spring 9 but normally held in a closed position (as shown in Figure 1) by a latch 10 pivoted as at 11 to the right end portion 12' of a guide rail 12 which extends laterally along the front of the machine. Respectively carried by the endgate 8 and standard 2 are conically pointed studs 14 and 15 which form right and left thrust bearings for a shaft 16. This shaft passes through an oversized hole 17 in the intermediate standard 3 and carries a mandrel 18 for holding a cylindrical record 19 to be resurfaced. In the operation of

mounting a record on, or removing a record from, the mandrel 18 the endgate 8 is swung open to free the right end of the mandrel. When the endgate is open the shaft 16 is intermediately supported by the standard 5, but is retained in engagement with the stud 15 by a collar 20, secured to the shaft by a screw 20', which abuts against the intermediate standard to limit the longitudinal movement of the shaft.

Supported by the left and right standards 2 and 4 is a longitudinal rod 21 on which there is slidably mounted a carriage 22 having a sleeve 23 embracing the rod as shown in Figure 2. The carriage 22 is substantially semi-circular in shape, curving forwardly from the rod 21 over the mandrel 18 and terminating in a relatively heavy front portion 22'. In the portion 22' there is provided a slot 24 which slidably fits on a forwardly extending shoulder 25 provided on and along the guide rail 12. The carriage is thus mounted for sliding movement back and forth across, and throughout the length of, the mandrel 18, but is prevented from being tilted upwardly by the engagement of the slot 24 with the shoulder 25.

On the right side of the carriage there is provided an extension 26, square-shaped as viewed from the side thereof, which substantially overlies the rod 21. This extension carries a resurfacing tool 27 comprising a knife blade 28 mounted on a knife bar 29 which is slidably supported by the extension 26 for movement towards and away from the record, the bar 29 being restricted against turning by a key 30 engaging a longitudinal slot 31 provided in the bar. The means for setting the resurfacing tool into operative position—a position of the tool in which the knife blade 28 engages the record—and for releasing the same therefrom may be substantially of a construction such as is described in my copending application Serial No. 232,766, filed October 1, 1938.

A tool-setting means of the above-mentioned type is shown in Figures 1, 2, 3, 4 and 5, and comprises an off-set gauge 32 to permit the setting of the tool while the tool is off the record. The gauge 32 is slidably supported by the extension 26 to the left of the knife bar 29, there being provided in the extension 26 left and right parallel openings 33 and 34, radially disposed with respect to the mandrel 18, through which the gauge and bar respectively pass. The bar and gauge are coupled to each other by means of an apertured link 35 which fits on reduced-diameter end portions 29' and 32' respectively provided along the upper parts of the bar and gauge, the link 35 being fastened on the reduced-diameter portion 32' of the gauge by a press fit but being freely slidable along the reduced-diameter portion 29' of the bar. The bar 29 is normally retained in a fixed position relative to the gauge by means of a relatively light compression spring 36 coiled about the reduced-diameter portion 29' of the bar between the link 35 and a lock nut 37 at the upper end of the bar. The gauge 32 is controlled by a cap 38 which slidably fits over the extension 26 and which is guided in its movement by a guide rod 39, secured to the cap and slidably passing through an opening 40 provided in the extension 26 in parallel relation to the openings 33 and 34. The cap 38 is apertured to slidably fit the reduced-diameter portion 32' of the gauge but is restricted in upward movement relative thereto by a head 41 on the gauge. The cap is normally held in contact with the head 41—i. e.,

urged upwardly relative to the gauge—by a compression spring 42 coiled about the reduced-diameter portion 32' of the gauge between the cap and the link 35, and the cap is moreover urged 5 upwardly relative to the carriage extension 26 by a relatively heavy compression spring 43 coiled about the guide rod 39. This upward urging of the cap 38 relative to the extension 26 normally retains the gauge 32 in unoperated position, defined by the contact of a collar 44 on the gauge with the underside of the extension 26. When the gauge 32 is in unoperated position the resurfacing tool 27 is biased into inoperative position by reason of the spring 36 which urges the 10 knife bar 29 upwardly into a position defined by the contact of a collar 45 on the bar with the underside of the carriage extension 26, an enlarged opening 46 being provided in the cap 38 to permit the knife bar 29, and lock nut 37 mounted 15 thereon, to pass freely therethrough in the movement of the resurfacing tool to inoperative position.

To set the resurfacing tool into operative position a downward movement is applied to the cap 25 38. The means for applying such downward movement to the cap comprises a tool-setting lever 46 pivotally supported by a post 47 provided on the right side of the carriage extension 26. The lever is retained on the post 47 by 30 means of a nut 48 and locking screw 49, and is connected to the cap 38 by a link 50 pivotally connected to an upwardly extending arm 46' of the lever 46 by a screw 51 and to the right side of the cap by the screw 52. The lever 46 is normally held in a position as shown in Figure 2 by reason of the upward biasing of the cap 38. When the lever 46 is turned in a counter-clockwise direction from the position just mentioned the cap is moved downwardly to move the gauge 40 32 and knife bar 29 towards the record, the link 50 being curved to clear a tool-locking means on the post 47, hereinafter described, in this counter-clockwise movement of the lever 46.

A downward movement of the cap 38 causes 45 both the gauge 32 and knife bar 29 to be yieldably moved, by reason of the spring 42, towards the record. The knife blade 28 on the knife bar will normally not contact the record in the setting of the resurfacing tool since, in the normal operation 50 of my invention, the resurfacing tool is set into operative position while the carriage is in the right end portion of its travel, the tool being then to the right of the record. The gauge 32, which is to the left of the tool, will, however, contact the record to define the operative position 55 of the tool relative to the record.

When the lever 46 is moved in a counter-clockwise direction, the tool is first moved into operative position and then, in the terminal movement of the lever, the tool is locked, thereby setting the tool. The tool-locking means is shown in Figures 2, 3, 4 and 5, and comprises a pin 53 which is slidably mounted in the carriage extension 26 for transverse movement relative to 60 the longitudinal movement of the knife bar 29. The inner end of the pin 53 slidably contacts a flat 54 on the knife bar, and the outer end extends slightly beyond the right side of the carriage extension. Pivoted on the post 47 between 65 the lever 46 and the carriage extension 26 is a disk-shaped locking member 55 having an open sector 55' of substantially 90° angular length and provided with an annular shoulder 55'' conveniently serving as a bearing for the tool setting lever 46. On the inner wall of the member 70

55 there is provided a beveled cam face 56. When the member 55 is turned in a counter-clockwise direction the cam face contacts the outer end of the pin 53 and presses the pin tightly against the knife bar to cause a locking of the bar against longitudinal movement. In order that such counter-clockwise movement of the member 55 will occur as an incident to the terminal movement of the lever 46, the lever 46 is provided with a lateral pin 57 which extends into the open 10 sector 55'. As the lever 46 is moved to set the tool the pin 57 first traverses the sector 55' and then encounters an edge 58, defining the counter-clockwise side of the open sector 55', to cause the member 55 to move in unison with the terminal 15 movement of the lever 46, thereby locking the resurfacing tool in operative position. When the lever 46 is next released it is returned in a clockwise direction by reason of the upward biasing of the cap 38, the pin 57 then traversing the open 20 sector 55' and the member 55 remaining in tool-locking position by reason of the friction between the pin 57 and the member. The resurfacing tool is thus maintained in operative position upon the release of the lever 46, but the gauge 32 is re- 25 tracted, or returned to its unoperated position, by the spring 43, the spring 36 being, however, compressed by the return of the gauge, as is indicated in Figure 4. Although the spring 36 resists the retraction of the gauge, the spring 43, 30 which urges the cap 38 upwardly, is made sufficiently strong to overcome the resistance of this spring. The spring 36 is, however, strong enough to return the resurfacing tool to inoperative position upon the unlocking of the tool, such tool- 35 unlocking occurring as an incident of moving the member 55 slightly in a clockwise direction to free the cam face 56 from the pin 53.

After the resurfacing tool is set into operative position the record is put in rotation and the carriage is moved steadily across the record in such direction as to cause a surface layer of the record to be cut away by the tool. This cut-away layer, commonly known as shaving chips, is caught by a chip chute 59 secured to the knife bar 29 by the 45 screw 59', which directs the chips downwardly through an opening 60 in the base plate, as for example, into a suitable container not shown.

In accordance with my invention the carriage 22 is reciprocated across the record for each 50 record resurfacing operation, this reciprocation being preferably from and to a start position at the left end of the record. During the first half cycle of such carriage reciprocation—i. e., during the time the carriage is traversing the record in a rightward direction—the resurfacing tool is in inoperative position and the mandrel 18 is stationary. At the completion of this first half cycle of carriage movement the carriage remains stationary for a predetermined time interval. During 60 this interval a series of automatic actions occur to cause the setting of the resurfacing tool into operative position and then the retraction of the tool-setting gauge 32, after which the mandrel is placed in rotation and the carriage is returned 65 through the last half cycle of its movement to start position to cause a resurfacing of the record. When the carriage has been returned to start position to complete one cycle of reciprocative movement across the record, the carriage movement and mandrel rotation are each stopped and the resurfacing tool is released to inoperative position, thus restoring the machine into normal inoperative condition. Upon restarting the machine the above cycle of operations is repeated: the car- 70 75

riage being first moved rightwardly into a position wherein the tool is to the right of the record, the movement of the carriage being next stopped, the tool being set, a mandrel rotation and a reverse carriage movement being next started, and then at the completion of the record resurfacing movement of the carriage the tool being released to inoperative position and the machine being stopped. In the description of the above operations the driving means for the machine may be first described.

The driving of the carriage 22, as well as the rotation of the mandrel 18, may be effected by a suitable motor M, schematically shown in Figure 9, which may be located beneath the base plate 1 and be coupled to a pulley 61 on the mandrel shaft 16 as by a suitable belt not shown which may pass through an opening 62 in the base plate. Integrally formed with the pulley 61 is a drive pulley 63 adapted to be coupled by a belt (not shown) to a pulley 64 provided at the left end of a laterally extending feed screw 65. This feed screw is rotatably supported by the standards 2 and 3 respectively carrying conically pointed studs 66 and 67 which serve as thrust bearings for the feed screw. Integrally formed with the carriage sleeve 23 is a block 68 (see Figures 1 and 3) to which is secured by screws 69 a resilient, rearwardly extending arm 70 carrying a feed nut 71 normally engaging the underside of the feed screw 65. Thus, a rotation of the feed screw causes the carriage to be fed, or driven steadily, along the mandrel, the direction of carriage movement depending upon the direction of rotation of the feed screw.

The motor M may be of a series type, comprising a field 72 and armature 73 adapted to be connected with a suitable source of power by way of a power supply circuit 74 and plug 75. While the field 72 and armature 73 are serially connected in the power supply circuit 74, the connection of the armature in the circuit is by way of a double-pole double-throw switch 76 operable to reverse the polarity of the armature relative to that of the field to control the direction of rotation of the motor. The switch 76 comprises pole members 77 and 78 serially connected with contact members 77' and 78' when the switch pole members are thrown to the left (as the switch appears in Figure 9) and with contact members 77'' and 78'' when the pole members are thrown to the right. The contact members 77' and 78' are directly connected by a circuit 79 with the armature 73, and are moreover connected in criss-cross fashion with the contact members 78'' and 77'', the contact members 77' and 78'' being connected together by a conductor 80 and the contact members 78' and 77'' being connected by a conductor 81, the conductor 81, however, serially including an adjustable resistor 82 and an openable and closable switch 83. When the switch 76 is thrown to the left the field 72 and armature 73 are directly and serially connected in the circuit 74 with such relative polarity as to cause the feed screw 65 to be rotated in a direction to move the carriage from left to right. When the carriage reaches the end of its rightward travel the switch 76 is automatically thrown to the right, as is herein-after described, to reverse the direction of rotation of the motor M so that the carriage will be next returned to the left. The rate of the motor speed during the return or leftward movement of the carriage is controlled by an adjustment of the resistor 82, this adjustment being such as to

effect a normal rate of record resurfacing movement of the carriage. Since the rightward movement of the carriage is an idle movement in the normal operation of the machine, by reason of the resurfacing tool being then not set in operative position, the carriage is permitted to move rightwardly at a relatively high rate of speed, this increased speed being caused by reason of the resistor 82 being then out of the motor circuit.

The integral pulleys 61 and 63 are mounted for rotation on the mandrel shaft 16 by means of left and right ball-bearing assemblies 84 and 85 interposed between the pulleys and the shaft and respectively fitting into left and right annular recesses 84' and 85' provided in the pulleys (see Figure 1), the pulleys being restricted against longitudinal movement on the shaft in a rightward direction by the abutment of the right ball-bearing assembly 85 against a shoulder 86 on the shaft and against movement in a leftward direction by the abutment of the left bearing assembly 84 against a stop collar 87 on the shaft.

While the pulleys as above described are freely rotatable in either direction on the mandrel shaft 16 there is provided a one-way action clutch means for causing the mandrel shaft 16 to be gripped to the pulleys when the pulleys are turned in one of their movable directions. This one-way action clutch means is illustrated in Figures 1 and 8 and comprises an annular flange 88 extending rightwardly from the rim of the pulley 61. To the right of the pulley 61 and within the flange 88 there is provided a disk 89. This disk is rotatably free of the pulley 61 and flange 88 and is secured to the mandrel shaft 16 by a pin 90 extending through the hub 89' of the disk. As shown in Figure 8, the disk 89 is provided with a plurality (three in the present instance) of notches 91 cut in the periphery of the disk at equal angular distances from each other. These notches extend axially through the disk and are each right-angular in cross section, having one side 91' in radial alignment with the disk and the other side 91'' extending from the side 91' in a counterclockwise direction about the disk, as shown in Figure 8. Provided in each of the notches 91 is a laterally extending roller 92 of a length substantially equal to the width of the disk, the rollers being retained in their respective notches by the right wall 61' of the pulley 61 and by an annular plate 93 secured to the right wall of the disk 89 by rivets 93'. Provided in the side 91' of each of the notches 91 is a recess 94 forming seats for respective compression springs 95 which urge the respective rollers 92 each in a counter-clockwise direction. The rollers 92 by reason of their biasing are normally wedged between the flange 88 and the side 91'' of each of the notches 91 to cause the disk to be normally rotatably coupled to the flange. When the flange is turned in a counterclockwise direction this wedging of the rollers causes the mandrel shaft to be turned in unison with the pulley 61. When the flange 88 or pulley 61 is, however, turned in a clockwise direction the rollers 92 are each continually moved against their biasing and out of their wedged positions abovementioned, as by the friction between the flange and the rollers. In the clockwise movement of the pulley 61 the mandrel shaft 16 is thus no longer rotatably coupled therewith except for the friction between the pulleys 61 and 63 and the mandrel shaft, which friction arises from the contact of the flange 88 with the rollers

92 and from the bearing assemblies 84 and 85. In the rightward movement of the carriage across the mandrel the pulleys 61 and 63, as well as the feed screw 65, are each turned in a clockwise direction as viewed from the right sides thereof. During such rotation of the pulley 61 the clutch between the pulley 61 and mandrel shaft 16 is maintained inoperative, as above described. However to insure that the mandrel 10 will not then be rotated by reason of the friction between the pulley 61 and mandrel shaft 16, as above noted, there is provided a mandrel brake (see Figures 1 and 3) comprising a lever 96 pivoted by a screw 97 to a bracket 98 secured to the top side of the base plate, to the rear of the standard 5, by the screws 99. The lever 96 is provided with a cross rod 100 carrying a shoe 101 which is adjacent to the left end of the mandrel. The lever 96 is biased over center by a tension spring 102 connected between a pin 103 on the lever and a pin 104 on the base plate. This biasing of the lever 96 causes the brake to snap into inoperative position, defined by the contact of the lever 96 with a stop pin 105 on the base 25 plate 1, and operative position, defined by the contact of the shoe 101 with the adjacent end of the mandrel, as the lever is moved through dead center in the direction to place the brake in inoperative and operative positions. When the 30 brake is brought into operative position the friction between the shoe 101 and the mandrel causes the mandrel rotation to be retarded. During the first half cycle of each carriage reciprocation—as when the carriage is moved to the right—the 35 mandrel brake is maintained in operative position to hold the mandrel against rotation, as is hereinabove described.

The means for placing the driving means in operation to start a feeding of the carriage in a 40 rightward direction across the mandrel comprises the aforementioned reversing switch 76 schematically shown in Figure 9. This switch is preferably of the well-known toggle variety (see Figures 1 and 2) having a threaded neck portion 106 from which extends an arm 107 adapted to snap 45 into its respective positions. The switch 76 is mounted on a bracket 108 secured by the screws 109 to the flange 1' of the base plate in the front right-hand portion thereof. The bracket is 50 apertured to receive the neck portion 106 of the switch, the switch being retained to the bracket, by a collar 110 threading on the neck portion, in such orientation as to bring the movement of the switch arm in a vertical direction. Pivoted by a 55 screw 111 on a boss 112 extending inwardly from the portion of the flange 1' which lies along the right side of the base plate is a relatively long lever 113 extending from front to back beneath the machine. The front portion 113' of the lever 60 is offset to the left and apertured to receive the switch arm 107. Extending up from the front portion 113' of the lever is a relatively short arm 114 provided with a fingerpiece 115 which passes through an opening 116 in the top of the base 65 plate. When the arm 107 of the switch 76 is in an upward position the fingerpiece projects slightly above the base plate as shown in Figure 2. This upper position of the arm 107 represents the condition of the switch 76 when its pole members 117 and 118 respectively make connection with the contact members 117' and 118', this being the condition of the switch to cause a leftward or record-resurfacing movement of the carriage. When the carriage is at start position the aforementioned switch 83 is retained in open position 70

to render the driving means inoperative, as is hereinabove described. However, upon moving the fingerpiece 115 downwardly the arm 107 of the switch 76 is thrown to cause its pole members 117 and 118 to make contact with the respective contact members 117' and 118'. This places the motor M in operation to cause a relatively fast rightward movement of the carriage across the record, the mandrel 18 remaining, however, stationary. 10

When the carriage nears the end of its rightward travel it causes a cam mechanism 117 to be set into operation to first stop the carriage movement by disengaging the feed nut 71 from the feed screw 65 and then to set the resurfacing tool into operative position, after which the cam mechanism moves the mandrel brake to inoperative position, re-engages the feed nut with the feed screw and reverses the direction of rotation of the motor M to cause record rotation and a 20 return feed or record resurfacing movement of the carriage. 15

The cam mechanism 117 is disposed beneath the base plate 1 in the rearward right-hand portion thereof, as shown in Figures 1, 2, 6 and 10, and comprises four differently shaped cam members 118, 119, 120 and 121 mounted from left to right on a laterally extending shaft 122 rotatably supported at its left end by a standard 123 extending downwardly from the base plate and at its right end by a leg 124 extending downwardly from the flange 1' of the base plate, the shaft being restricted against longitudinal movement in its bearings by a pair of stop collars 125 and 126, secured to the shaft by the respective pins 125' and 126', which respectively abut against the left and right sides of the standard 123. While the several cam members are comparable with each other in diameter, cam members 118 and 120 are substantially longer in their axial dimensions 30 than the cam members 119 and 121, the cam members 118 and 120 respectively having annular recesses 118' and 120' cut in from the right sides thereof to reduce their respective weights, as shown in Figure 11. The cam members of the 35 pair 118—119, as well as those of the pair 120—121, are immediately adjacent to each other, but the cam members 119 and 120 are spaced a small distance from each other along the shaft. The several cam members are, however, rotatably connected together, for rotation in unison with each other, by press fitting each of the cam members on a sleeve 127 (see Figure 11). The sleeve 127 embraces the shaft 122 and is slightly hollowed out along its central portion to provide 40 left and right bearing surfaces 128 and 129 of the sleeve on the shaft. The sleeve, and cam members fixedly mounted thereon, are thus freely rotatably mounted on the shaft 122; but are restricted against longitudinal movement on the 45 shaft, the restriction in rightward and leftward directions being effected by the respective abutments of the sleeve 127 against the leg 124 and an annular ring 122' integrally formed with the shaft. 50

During the operation of the machine the shaft 122 is rotated continuously, being driven by the feed screw 65 from a worm 130 provided on a shaft portion 65' at the right end of the feed screw. Engaging the worm 130 is a gear 131 secured by a pin 131' to a vertical shaft 132 rotatably mounted in and passing through a long boss 133 which extends above and below the base plate 1. Secured by a pin 134' to the lower end of the shaft 132 is a bevel gear 134 which 55 60 65 70 75

engages with a similar bevel gear 135 secured to the shaft 122 by a pin 136. The direction of the coupling between the feed screw 65 and the shaft 122 is such that when the feed screw is turned in a clockwise direction—the direction for imparting a rightward movement to the carriage 22—the shaft 122 is also turned in clockwise direction, this direction of turning of the shaft 122 being of course reversed when the direction of rotation of the feed screw is reversed to return the carriage to its start position.

The cam members 118, 119, 120 and 121 are normally held in their initial or start position—the position in which they are shown in the figures—by the engagement of a detent 128, secured to the leg 124, with a notch 121' on the right face of the cam member 121. The cam members may, however, be rotatably connected to the shaft 122 by means of a clutch 137 comprising a toothed clutch member 138 splined to the shaft 122 for movement between the gear 135 and the cam member 118. This splining is done by means of a pin 139 extending through the hub of the clutch member and engaging a groove segment 140 extending longitudinally of the shaft, as is shown in Figure 11. When the clutch member 138 is moved to the right into contact with the cam member 118, it engages a tooth 141, provided on an annular flange 141' extending leftwardly 30 of the cam member, to rotatably couple the cam members with the shaft 122.

The means for controlling the clutch 137 comprises an over-center mechanism adapted to urge the clutch into its engaged and disengaged positions depending upon the direction in which the mechanism is thrown. This over-center mechanism, shown in Figures 6 and 10, comprises a relatively long arm 142 pivoted to a boss 143 extending downwardly from the base plate at a point slightly to the rear of the clutch member 138. The arm 142 extends forwardly from its axis over the clutch member 138 and carries, at a point directly overlying the clutch member 138, a pin 144 which extends downwardly to engage an annular groove 138' in the clutch member. Pivoted by a screw 145' on the forward end of the arm 142 is an upstanding post 145 having a radially extending rod 146 near the upper end thereof. Substantially above the post 145 is a relatively short lever 147 which is pivoted at a point substantially centrally of its length to a boss 148 extending downwardly from the base plate. The lever 147 is restricted in its turning to small angular movements in clockwise and counter-clockwise directions from a central or front-to-back extending position as is herein-after described. Pivoted to the rearward end of the lever 147 by a shoulder screw 150' is a post 150 extending downwardly from the lever and apertured near its lower end to receive the rod 146. Coiled about the rod 146 between the posts 145 and 150 is a relatively heavy compression spring 151. When the lever 147 is moved in a counter-clockwise direction through its central position until the post 150 carried by the lever is slightly to the left of the post 145 carried by the arm 142 the compression spring 151 urges the arm 142 in a rightward direction to cause the engagement of the clutch 137, and when the lever 147 is returned in a clockwise direction until the post 150 is slightly to the right of the post 145, the spring 151 urges the arm 142 leftwardly to cause the disengagement of the clutch.

75 The lever 147 is biased in a counter-clockwise

direction—the direction of movement of the lever to cause engagement of the clutch 137—by a tension spring 152 connected between the lever and a pin 153 on the base plate. The lever 147 is controlled in its movement by the contact of the front tip 147' of the lever with a catch 154 on a laterally extending and relatively long pawl 155 pivoted at its right end, by a screw 156, to the left end of a slide member 157. This member 157 is mounted for lateral movement by means of a pair of shoulder screws 158 respectively passing through a pair of elongated slots 159 in the member to thread into a pair of bosses 160 extending downwardly from the base plate. The member 157 is normally retained in its most leftward position shown in Figure 6, as is hereinafter described; the pawl 155 is urged rearwardly in a clockwise direction into its normal position, defined by the contact of a stop lug 161 on the pawl with the rear edge 157' of the member 157, 20 by a tension spring 162 connected between the stop lug 161 and a lug 163 turned down from the member 157. When the member 157 and pawl 155 are in such respective normal positions the lever 147 is retained, against its biasing, by the 25 contact of its tip 147' with the catch 154 in its clockwise position shown in Figure 6, the clutch 137 being then disengaged as above described.

When the pawl 155 is tripped—i. e., turned in a counter-clockwise direction to release the catch 154 from the lever 147—the spring 151 moves the lever 147 in a counter-clockwise direction, as against a stop pin 164 extending downwardly from the base plate, to cause the engagement of the clutch 137. Such tripping of the pawl 155 is effected by the carriage 22 when the carriage nears the end of its rightward travel across the record. The means for causing this tripping by the carriage comprises a lever 165 pivoted by a screw 166 to a boss 167 extending downwardly from the base plate. The lever 165 extends rearwardly from its axis and carries a relatively long vertical pin 168, near its rearward end, which extends upwardly through an arcuate opening 169 in the base plate, the lever being 45 normally held in a leftward position defined by the contact of the pin 168 with the left end of the opening 169 by a tension spring 170 connected between the lever and a pin 171 on the base plate. Provided on the lever 165 near its 50 axis is a short rightwardly extending arm 172 on which there is pivoted as at 173 a V-shaped pawl 174 which is biased in a counter-clockwise direction into a position defined by the contact of a stop lug 175 on the pawl with the right edge 165' of the lever 165, the biasing being done by a tension spring 176 connected between the stop lug 175 and a lug 177 turned down from the lever 165. As the carriage nears the end of its rightward travel, a rightward extension 178' of a rearwardly 60 and downwardly extending arm 178, which is secured to the carriage sleeve 23 by a clamp 179, encounters the pin 168 of the lever 165 to cause a rightward or clockwise movement of the lever. As the lever 165 is so moved the pawl 174 impinges upon the pawl 155 and thereby moves the pawl 155 to free the catch 154 from the lever 147 (the pawl 174 having its end portion which impinges upon the pawl 155 increased in thickness by the 70 welding of a piece 174' thereon, as shown in Figures 6 and 10). The lever 147 then moves, as because of its biasing, in a counter-clockwise direction to cause the engagement of the clutch 137.

When the clutch 137 is engaged by the carriage the cam members 118, 119, 120 and 121, by reason of their coupling to the shaft 122, are turned in unison in a clockwise direction from their initial or start position. In substantially one revolution of the cam members, a series of actions take place to cause the machine to be conditioned to effect a record resurfacing operation.

One of the above series of actions is to prepare for operation the means for disengaging the clutch 137—i. e., to move the member 157 rightwardly to get the tip 147' of the lever 147 to snap over the catch 154 of the pawl 155 so that upon the return or leftward movement of the member 157 the lever 147 will be moved to cause the disengagement of the clutch. The means for moving the member 157 rightwardly comprises a relatively long arm 180 which extends rearwardly of the member 157 to terminate at a point overlying the cam member 120. At the end of the arm 180 there is provided a downwardly extending pin 181 which engages an angular cam groove 182 (see Figure 6) which extends through approximately one revolution about the periphery of the drum shaped cam member 120. The groove 182 starts at the left edge of the cam member and moves in a relatively short portion 182' of its angular length, proceeding in a counterclockwise direction about the cam member, to the right side of the cam member, the groove then remaining or dwelling throughout the remaining portion of its angular length at the right side of the cam member. When the clutch 137 is engaged the cam member 120 starts immediately to turn in a clockwise direction. The initial clockwise movement of the cam member 120 causes the member 157 to be moved rightwardly until the catch 154 is snapped over the tip 147' of the lever 147. In the further clockwise movement of the cam member 120 the member 157 dwells in its rightward position, the member 157 remaining in this position until the cam member 120 is returned sufficiently in a counter-clockwise direction to cause the pin 181 to re-engage the curved portion 182' of the cam groove as is hereinafter described.

While I have here shown and described the preparing of the means for disengaging the clutch 137 as occurring during the initial clockwise movement of the cam mechanism 117, it will be understood that this preparing may occur at any time during the functioning of the cam mechanism so long as it occurs before the function of the cam mechanism is completed, leaving the cam mechanism to cause the disengagement of the clutch 137 as its final action.

Another in the series of actions automatically performed by the clockwise movement of the cam mechanism 117 is the setting of the resurfacing tool into operative position. Before this tool setting takes place I prefer that the carriage movement be stopped so as to permit an accurate setting of the resurfacing tool on the record; it is, however, to be understood that a stopping of the carriage is not necessarily essential to the operation of my invention, particularly since the provision of a tool-setting gauge, heretofore described, enables the setting of the tool with a high degree of accuracy while the carriage is yet being fed across the record. A means for stopping the movement of the carriage is shown in Figures 1, 2, 7 and 10, and comprises a relatively long, laterally extending lever 183 pivoted centrally thereof by a pin 184 to the top of a post 185 extending upwardly from the base plate at a

point slightly to the rear and to the left of the standard 3. The left end portion 183' of the lever terminates at a level just above a rearward extension 70' of the feed nut supporting arm 70, the right portion of the lever 183 being offset slightly to the rear to clear the standard 3 and terminating in a downwardly extending arm 186, turned over from the lever. Pivoted to the lower end of the arm 186, by a pin 188, is a relatively short arm extension 189 which passes through an opening 187 in the base plate. This arm extension is normally held in a substantially downward but slightly rearwardly inclined position relative to the arm 186, as against a stop lug 190 on the arm 186, by a tension spring 191 connected between a turned-over lug 192 on the arm extension 189 and the stop lug 190. The lever 183 is biased in a clockwise direction as viewed from the front, by a tension spring 194 connected between the lever 183 and a pin 195 on the standard 3, to urge the arm extension 189 downwardly towards the cam member 119. The arm extension 189 is, however, normally held just free of the cam member 119 by a stop pin 193 on the standard 3 which restricts the movement 25 of the lever 183 in its biased direction. When the cam member 119 is turned in a clockwise direction through approximately 45° from its initial position, the arm extension 189 encounters an inclined cam face 196 forming the start of a 30 ridge 196 which extends around the rim 119' of the cam member to within approximately 25° of the position on the cam member which is adjacent the arm extension 189 when the cam member is in its initial position. By the contact of the arm 189 with the face 196', the lever 183 is tilted in a counter-clockwise direction. When this tilting occurs the carriage is in the end portion of its rightward travel with the left end 183' of the lever 183 directly above the rearward extension 70' of the feed nut supporting arm 70. Thus, in the tilting of the lever 183 the end 183' thereof impinges upon the extension 70' to move the feed nut 71 downwardly out of engagement with the feed screw 65, thereby stopping the 40 movement of the carriage. In the further clockwise movement of the cam member subsequent to the contact of the arm 189 with the cam face 196', the feed nut is retained out of engagement with the feed screw, by the contact of the arm 189 with the ridge 196, the feed nut being re-engaged with the feed screw when the arm extension 189 moves off from the end 196'' of the ridge as is later explained.

It is important that the carriage be retained in the end portion of its rightward travel during the time the feed nut is disengaged from the feed screw in order that the resurfacing tool may be set into operative position while the tool is yet off the record. In order to prevent possible 55 accidental manipulations of the carriage during the time the feed nut is disengaged from the feed screw, there is provided in the extension 70' of the feed nut supporting arm a notch 70'' which, as the extension 70' is moved downwardly by the 60 lever 183 to disengage the feed nut from the feed screw, engages a post 149 extending up from the base plate 1, thereby locking the carriage.

The action which is next performed by the cam mechanism 117 after the stopping of the carriage 70 is the setting of the resurfacing tool into operative position. The means for setting the tool is shown in Figures 2, 7 and 10 and comprises a rocker arm 197 pivoted centrally thereof by a screw 198 to the upper end of an upright support 75

199 secured to the right side of the standard 3 by the screws 200. The support 199 is offset to the right in order to position the rocker arm 197 so that its forward end portion 197' will be directly below a cross pin 201, carried on a rearwardly extending arm 46" of the tool-setting lever 46, when the carriage is in the end portion of its rightward travel. A rocking of the arm 197 in a direction to raise its forward end portion 197'—i. e., a clockwise turning of the rocker arm 197 as it appears in Figure 2—will then impart a counter-clockwise or tool-setting movement to the lever 46.

The means for so moving the rocker arm 197 comprises a link 202 pivoted by a screw 203 to the rearward end of the rocker arm. Forming a downward extension of the link 202 is a bar 204 which is adjustably connected to the link by a pair of shoulder screws 205, the screws passing through a pair of respective slots 206 in the link 202 to thread into the bar. The bar 204 extends downwardly through the opening 187 in the base plate and terminates in a yoke 204' disposed between the cam members 119 and 120 and provided with an elongated slot 207 through which passes the sleeve 127 on which the cam members are mounted. The sleeve thus restricts the movement of the yoke 204' to straight up and down reciprocative motion. In order to impart such motion to the yoke 204' by the clockwise turning of the cam mechanism 117 the yoke 204' is provided with a pin 208 which engages a cam groove 209 provided in the right face of the cam member 119, as shown in Figure 7. When the cam mechanism 117 is in initial position the forward end portion 197' of the rocker arm 197 is positioned slightly below and suitably free of the pin 201 of the tool-setting lever 46, this positioning of the rocker arm 197 being controlled by the adjustable connection of the link 202 to the bar 204.

In proceeding in a counter-clockwise direction about the cam member 119 from the position in the cam groove 209 occupied by the pin 208 when the cam mechanism is in its initial position as shown in Figure 7, it is seen that the groove 209 dwells along the rim 119' of the cam member 119 through an angular length exceeding the angular distance between the initial point on the cam member and the cam face 196' aforementioned, this angular length of the groove being approximately 90°. In proceeding further around the cam member 119 through approximately 135° it is seen that the groove 209 curves inwardly as at 209' towards the axis of the cam member; in proceeding still further through approximately 120° it is seen that the groove curves outwardly, as at 209'', towards the rim 119' of the cam member. Thus in approximately one revolution of the cam member 119 in a clockwise direction the groove 209 moves in the radial direction of the cam member from its rim to substantially its axis and back again to its rim. In this movement of the cam member the yoke 204' is moved, by the engagement of the pin 208 with the groove 209, first downwardly and then upwardly to complete one cycle of reciprocative movement. The first half cycle of this movement—i. e., the downward stroke of the yoke 204'—moves the rocker arm 197 in a clockwise direction to impart a counter-clockwise or tool-setting movement to the lever 46, the first portion of this movement of the lever 46 causing the tool to be moved into operative position and the terminal movement 75 of the lever 46 causing the tool to be then locked

or set in its operative position as heretofore described. In the second half cycle of the movement of the yoke 204'—i. e., its upward movement—the rocker arm 197 is returned in a counter-clockwise direction to permit the tool-setting lever 46 to return by its biasing to its unoperated position, the tool remaining, however, locked in its operative position. 5

It is seen that when the cam mechanism 117 is moved through approximately two-thirds of one revolution in a clockwise direction, the carriage is first stopped and the tool is next set into operative position. The automatic action next performed by the cam mechanism 117 after the setting of the tool is the release of the mandrel 10 brake, hereinbefore described, from operative position. To release the brake there is provided a slide bar 211 which extends laterally of the machine just above the base plate and slightly to the rear of the longitudinal rod 21. The slide bar 20 211 is mounted on left and right bosses 212 and 213 on the base plate by a pair of shoulder screws 214 and 215 which pass through respective slots 216' and 215' in the slide bar to thread into the respective bosses 212 and 213. At the left end 25 of the slide bar there is provided a hook 216. This hook is adapted to catch on a turned-down lug 217 on the lever 96 of the mandrel brake to release or move the mandrel brake to inoperative position as the slide bar is moved to the right. 30 To cause such rightward movement of the slide bar there is provided on the bar at its rightward end a right-angle arm 218 which extends downwardly through an opening 219 in the base plate and then rearwardly, at the level of the top of 35 the cam member 119, to a position overlying this cam member. The cam member 119 is in the shape of a drum having a cam extension 220 provided thereon which starts at a point at about two thirds the angular distance about the cam 40 member proceeding in a counter-clockwise direction. Extending downwardly from the rearward end of the arm 218 is a pin 221 which, in the last one third clockwise movement of the cam member 119, is impinged upon by the cam extension 45 220 to cause the slide bar 211 to be moved to the right to release the mandrel brake.

The action which is caused to occur by the cam mechanism 117 subsequent to the release of the mandrel brake is the re-engagement of the feed 50 nut 71 with the feed screw 65. Reference being had to Figure 7 it will be seen that the ridge 196 on the cam member 119 terminates as at 196'' at a point which is approximately 25° from the point on the cam member which is adjacent the 55 arm extension 189 when the cam mechanism 117 is in its initial position. Thus, when the cam member 119 has been moved in a clockwise direction through approximately 335° the arm extension 189 rides off from the ridge 196 to permit the 60 lever 183, which is controlled by the cam member 119, to turn in a clockwise direction by reason of its biasing until the lever is stopped by the stop pin 193 as heretofore described. This clockwise turning of the lever 183 is sufficient to free the 65 left end portion 183' of the lever from the extension 70' of the feed nut supporting arm, the upwardly biased supporting arm 70 then moving upwardly to unlock the carriage by the freeing of the notch 70'' from the post 149 and to re-engage 70 the feed nut with the feed screw.

The last in the series of actions caused by substantially one revolution in a clockwise direction of the cam mechanism 117 is the throwing of the reversing switch 76 to reverse the direction of 75

rotation of the motor M. It will be recalled that to start the machine the fingerpiece 115 is moved downwardly to cause the switch arm 107 to snap into its downward position, thereby throwing the 5 switch pole members 77 and 78 to the left as they appear in Figure 9. To reverse the motor M it is only necessary to move the switch arm 107 upwardly to cause the pole members 77 and 78 to be thrown to the right. To effect this throwing of 10 the switch the lever 113 is extended rearwardly and downwardly from its axis to terminate in a finger 222 which is radially in line with the cam member 121. The cam member 121 is in the form of a relatively thin disk having a short cam extension 223 on its periphery. When the fingerpiece 115 is moved downwardly to start the machine the finger 222 is moved substantially into contact with the disk portion of the cam member 121. The cam member 121 is so oriented on its 15 shaft that when the cam mechanism is in its initial position the cam extension 223 is displaced approximately 15° in a clockwise direction from the finger 222. Thus when the cam member 121 is moved approximately 345° in a clockwise direction, which is approximately 10° further than the rotation required to re-engage the feed nut with the feed screw, the cam extension 223 impinges upon the finger 222 and moves the lever 113 in a direction to cause the arm 107 of the switch 16 20 to be moved upwardly, thereby reversing the motor M.

It will be seen that in the interval between the time the feed nut is re-engaged with the feed screw and the time the switch 16 is thrown to 25 reverse the motor M, the carriage is moved to the right. The cam mechanism may be arranged so that this time interval is relatively short, the necessary time interval being only that which is required to positively insure the re-engagement of 30 the feed nut with the feed screw before the reversing of the motor M. In the present instance, the feed nut is re-engaged with the feed screw when the cam mechanism has turned approximately 335° and the motor is reversed when the 35 cam mechanism is turned approximately 345°, the rightward movement of the carriage thus occurring only during a 10° movement of the cam mechanism.

Upon the reversal of the motor M the cam 40 mechanism 117 is immediately started in a reverse or counter-clockwise direction and the mandrel 18 is set in rotation by reason of the one-way action clutch which couples the pulley 61 to the mandrel shaft 16. There is also immediately 45 imparted to the carriage a record resurfacing movement—i. e. a movement in a leftward direction—by reason of the feed nut being engaged with the feed screw at the time the motor M is reversed. In order that the feed nut will be retained in engagement with the feed screw during 50 the reverse or counter-clockwise movement of the cam mechanism 117 the arm extension 189 is pivoted on the arm 186, as heretofore described. In the counter-clockwise movement of the cam 55 member 119 the end 196' of the ridge 196 encounters the arm extension 189 and moves it forwardly against the biasing of the spring 191, the lever 183 remaining during this time in its biased position, defined by the contact of the lever with 60 the stop pin 190, wherein the lever is free of the extension 70' of the feed nut supporting arm.

The reverse or counter-clockwise movement of 65 the cam mechanism 117 to its initial or start position is completed during the first portion of the leftward or record resurfacing movement of the 70

carriage. At the time the motor M is reversed the pin 208 occupies the position in the cam groove 209 as shown in dash dot lines in Figure 7. During the reverse or counter-clockwise movement of the cam mechanism the tool-setting mechanism is adapted to remain inactive, this being permitted by the provision of a groove 224, which extends along the rim 119' of the cam member 119, through which the pin 208 may pass. In order to insure that the pin 208 will enter the groove 224 in the reverse movement of the cam mechanism the yoke 204' is biased upwardly, by a tension spring 199' connected between the rocker arm 197 and its support 199, to cause the pin 208 to move upwardly against the rim 119' of the cam member 15 as soon as the pin has passed out of the groove portion 209' in the final portion of the clockwise movement of the cam mechanism. As the pin 208 traverses the groove 224 it encounters a tongue-shaped member 225 which normally forms a separation between the groove 224 and the groove 209. The member 225 is pivoted at 226 to the cam member and is biased outwardly against the rim 119' by a small leaf spring 227 provided in a small recess 228 in a raised portion 229 of the cam face which divides the cam grooves 209' and 209'' from the cam groove 224, the spring 227 having a bracket extension 227' at one end which is secured to the cam member as by welding and contacting a short arm 230 of the tongue 225 at its other end. As the pin 208 traverses the groove 224 in the counter-clockwise movement of the cam member 119 the pin encounters the outer edge 225' of the tongue-shaped member 225 and moves it inwardly and then moves on to enter the cam groove 209, the member 225 snapping back against the rim 119' when the pin has entered the cam groove 209. During the clockwise movement of the cam member, the pin encounters the inner edge 225'' of the tongue 225 and is thereby directed into the cam groove 209' as heretofore described. 30

During the final return movement of the cam mechanism 117 the arm extension 189, when it rides off of the ridge 196 by way of the cam face 45 196', snaps back into its normal position as because of its biasing spring 191. Also in the final return movement of the cam mechanism the member 157 is moved to the left by the engagement of the pin 181 with the curved portion 182' of 50 the cam groove 182 of the cam member 120. This leftward movement of the member 157 causes the lever 147 to be turned in a clockwise direction by its contact with the catch 154. When the member 157 has reached its most leftward position 55 as defined by the engagement of the pin 181 with the end of the cam groove 182' the lever 147 has been turned sufficiently to cause the arm 142 to snap over center to the left to cause the clutch 137 to be disengaged. The cam mechanism 117 is then 60 fully returned to its initial position and in condition for re-operation, the cam mechanism being retained in this position during the time the clutch 137 is disengaged by the detent 128.

During the return of the cam mechanism the 65 carriage is moving to the left. Normally the carriage will be fed sufficiently to the left to permit the full return of the lever 165, which is controlled by the carriage, before the member 157 is moved enough leftwardly to bring the tip of the pawl 155 70 into the path of the pawl 174, thus normally insuring that the pawl 174 will get behind the pawl 155 before the latter pawl enters the path of the former. If under any circumstances the pawl 174 should get in front of the pawl 155 in its 75

return movement it will snap over the pawl 155 into normal position relative thereto when the lever 165 is returned into its most leftward position.

5 When the carriage nears its start position, the resurfacing tool having moved to the left of the record, a lever 231 which is pivoted on the right side of the carriage by a shoulder screw 232 is automatically turned to cause the release of the 10 resurfacing tool to inoperative position. Reference being had to Figures 1, 2 and 3, it will be seen that the lever 231 is provided with a forwardly extending arm 233 normally contacting the underside of a forward extension 234 of the tool-locking 15 member 55, and with an arm 235 which extends downwardly to the rear of the carriage. Secured to the top side of the base plate by the screws 236 is an upstanding bracket 237 having a turned over cam 238 lying in the terminal path of the 20 arm 235. When the carriage enters its start position the cam 238 impinges on the arm 235 and thereby turns the lever 231 slightly in a clockwise direction. This turning of the lever 231 imparts, as by the contact of the arm 233 with the extension 234, a clockwise movement to the member 55 25 to cause the release of the resurfacing tool from its set position.

Secured on the rear end of the carriage by the screws 239 is a short downwardly extending arm 30 240 which, as the carriage nears its start position, contacts the lever 96 of the mandrel brake and moves the lever in a counter-clockwise direction through its dead-center position, the lever being then moved onwardly in a counter-clockwise 35 direction by the spring 102 until the shoe 101 of the mandrel brake impinges against the mandrel 18 to render the mandrel brake operative. In the counter-clockwise movement of the lever 96 to render the mandrel brake operative the lug 40 217 of the lever 96 impinges against the hook 216 of the slide bar 211 and moves the bar leftwardly, the pin 221 being at this time free of the cam extension 220 of the cam member 118, by reason of the cam mechanism 117 being in its initial position, to permit the slide bar to be so moved.

45 In accordance with my invention, when the carriage is returned to start position to complete one cycle of reciprocal movement across the record the carriage not only causes the automatic 50 actions above described but also causes the stopping of the machine. The stopping of the machine may very appropriately occur as an incident to the placing of the mandrel brake into operative position. It is seen that when the carriage 55 moves the lever 96 through dead center position the lever is moved onwardly by the spring 102 to render the mandrel brake operative. This final movement of the lever 96, which is caused by the spring 102, opens the aforementioned switch 83, this opening of the switch 83 60 causing the machine to be stopped since the switch is serially included in the power supply circuit 74 of the machine when the reversing switch 76 is thrown to cause a return or leftward movement 65 of the carriage. Reference being had to Figures 1 and 10 it will be seen that the switch 83 comprises a frame 241, secured to the top side of the base plate in the rearward left-hand portion thereof by the screws 242, and having a stack 243 70 insulatedly carrying a pair of forwardly extending left and right contact springs 244 and 245 biased into a normally closed condition. These contact springs 244 and 245 are connected by means of a cable 246, which passes through an opening 247 75 in the frame 241, into the motor circuit. Secured

to the left contact spring 244 is an insulating bar 248 which extends forwardly from the switch by way of an opening 248' in the frame 241 into a position directly to the left of the slide bar 211. When the slide bar 211 is moved leftwardly by 5 the final movement of the lever 96 to place the mandrel brake into operative position, the slide bar impinges upon the bar 248 and thereby moves the contact spring 244 leftwardly to break connection with the contact spring 245, the motor 10 circuit 74 being thus opened to stop the machine.

In recapitulation, it is seen that the switch 83 is included in the motor circuit until the machine is restarted to produce a rightward movement of the carriage by throwing the reversing switch 76. 15 When the carriage reaches the end of its rightward travel the switch 76 is automatically reversed to again include the switch 83 in the motor circuit; however, before the switch 76 is thrown to reverse the machine the mandrel brake is 20 released or moved to inoperative position. This release of the mandrel brake permits the switch 83 to close by its own biasing so that when the switch 76 is thrown to reverse the machine, the machine is rendered operative to effect a record 25 resurfacing movement of the carriage.

After the carriage has returned to start position, having moved back and forth across the record to complete a resurfacing operation on the record, the machine may be restarted to 30 complete another record resurfacing operation by throwing the switch 76, as by merely pressing the fingerpiece 115 downwardly to a position wherein it is substantially on the level with the base plate. In the proper operation of the machine 35 the switch 76 should be manually thrown to reverse the machine only when the carriage is in its start position since the mandrel brake is not rendered operative and the tool is not released until this position of the carriage is 40 reached. To prevent possible accidental manipulation of the switch 76 while the carriage is out of start position there is provided along the length of the guide rail 11 a bar 249 which is 45 slidably mounted for limited movement along the guide rail by a pair of screws 250 and 251 which pass through longitudinal slots 250' and 251' in the bar to thread into respective left and right bosses 250" and 251" extending forwardly of the guide rail. At the right end of the bar 249 there 50 is provided a turned-over lug 252. When the bar 249 is in its rightward position, as defined by the contact of the screws 250 and 251 with the slots 250' and 251', the lug 252 forms a cap over the fingerpiece 115 to prevent access thereto. The bar 249 is normally held in its most rightward position by a tension spring 253 connected between a pin 254 on the bar and a pin 255 on the guide rail. However, as the carriage is moved leftwardly into its start position—the 55 switch 76 having been reversed and the fingerpiece 115 being in an upward position as shown in Figure 2—the lower end of its front portion 22' impinges upon an upstanding hook 249' provided at the left end of the bar 249 and moves 60 the bar 249 leftwardly to move the lug 252 off from the fingerpiece 115. The fingerpiece 115 is then free to be manually moved downwardly to restart the machine.

If the operator should for any reason desire 70 to stop the operation of the machine during the course of a tool-carriage reciprocation across the record he may do so by throwing a single-pole single-throw switch 256, preferably of the toggle variety, which is serially included in the power 75

supply circuit 74 as shown in Figure 9. The switch 256 is shown in Figures 1 and 2 and is mounted in a recess 257 in the carriage 22 near the front portion 22' thereof. The switch 256 is provided with a threaded tubular neck portion 258 extending through the right wall of the carriage on which there is threaded a nut 259 to hold the switch in place. Extending from the neck portion 258 to the right of the carriage is an arm 260, and leading from the switch is a cable 261 by which the switch is connected in the power supply circuit 74. The switch is so oriented that the switch arm 260 will move in a substantially vertical direction, with upper and lower positions of the switch arm representing the closed and open conditions of the switch. To facilitate the operation of the switch there is provided a lever 262 which is pivoted by a shoulder screw 263 on the right side of the carriage, the lever being spaced from the carriage by a spacer 264 embracing the screw 263. The forward end of the lever 262 terminates in a handle portion 262'; just to the rear of the handle portion 262' are provided upper and lower turned-over lugs 265 and 266 to form a socket which engages the switch arm 260. Thus as the lever 262 is moved, as by its handle portion 262', into downward and upward positions the switch arm 260 is moved to throw the switch 256 into its open and closed positions to stop and start the machine. In order that the resurfacing tool may also be released to inoperative position as an incident to such stopping of the machine the lever 262 is extended rearwardly of its axis and there provided with a turned-over lug 267 adapted to form a seat which, when the lever 262 is moved downwardly to stop the machine, impinges upon a forwardly extending arm 268, provided on the tool-locking member 55, to move the member 55 in a clockwise direction and thereby effect the release of the resurfacing tool.

When the resurfacing of the record is completed, usually one cut from the record being sufficient, the record is removed from the machine.

To remove the record the endgate latch 10 is first moved to inoperative position to permit the endgate 8 to swing open, as by its biasing, and then the record is ejected from the mandrel. A record ejector of the type shown in the figures is well known in the art, and is sufficiently described as follows: A leftwardly extending handle 269 having a hub 270 is pivoted on a pin 271 supported at one end by the guide rail 12 and at the other end by the intermediate standard 5. From the hub 270 there extends a vertical arm 272 carrying a shoe 273 adapted to impinge against the left end of the record when the ejector is operated. The ejector is normally maintained in an unoperated position, shown in Figure 1, by a torsional spring 274 coiled about the hub 270 and constrained at its ends by the handle 269 and base plate 1. To operate the ejector the handle 269 is raised against the force of the spring 274 to move the shoe 273 rightwardly against the record to push the record off from the mandrel.

In accordance with my invention there may be provided means by which the machine is put into operation, as an incident to the mounting of a record on the machine, to cause a resurfacing of the record so mounted. The last of the operations in the mounting of a record on the machine is the latching of the endgate 8 into its closed position. This latching of the endgate 75 may cause the machine to be put into operation

to complete a resurfacing of the record, as by the means shown in detail in Figures 12 and 13. It is seen that the endgate latch 10 is in the form of a bolt 275 passing through a horizontal recess 276 in the right end portion 12' of the guide rail and connected to a vertical shaft 277 pivoted in an opening 12" extending downwardly from the recess 276 through the end portion 12' of the guide rail. The upper end portion 277' of the shaft 277 is reduced in diameter and threaded to receive a nut 278 which rests on the portion 12' to hold the shaft against downward movement; the intermediate portion 277" of the shaft is milled into the shape of a bar (see Figure 13) and the bolt 275 is apertured to receive this bar-shaped portion, thereby keying the bolt to the shaft. Secured to the lower end of the shaft 277, by a pin 279, is an arm 280 which extends rightwardly in line with the bolt 275 to terminate at a point overlying the lever 113. Pivoted on the lever 113, by a screw 281, is a V-shaped pawl 282 which is so disposed relative to the arm 280 as to lie directly in front of the arm when the endgate latch 10 is in operative position. The pawl 282 is biased in a clockwise direction towards the arm 280, against a stop lug 283 on the lever 113, by a tension spring 284 connected between the pawl and a lug 285 on the lever 113. When the endgate latch 10 is opened or moved to inoperative position the arm 280 impinges against the pawl and moves the pawl against its biasing, the arm thus sliding over the pawl and the pawl then snapping back into its biased position. When the endgate latch is moved to operative position the arm 280 impinges upon an inclined cam face 286 of the pawl and thereby moves the lever 113, which carries the pawl 282, downwardly to throw the switch 16 so as to start the machine. Thus by the locking of the endgate into closed or operative position—which is the final action in the mounting of a record on the machine—the machine is put into operation to effect a resurfacing of the mounted record.

While I have herein described and illustrated one embodiment of my invention it will be understood that this embodiment is subject to many changes and modifications without departure from the scope of my invention, which I undertake to express according to the following claims.

I claim:

1. In a phonograph record resurfacing machine having a record support and a carriage: the combination of a resurfacing tool on said carriage settable into operative position relative to a record on said support; driving means for feeding said carriage across said support; and means effective without prior adjustment of the tool relative to the record and operated by said driving means to automatically set said tool into operative position.

2. In a phonograph record resurfacing machine having a record support: the combination of a carriage; a resurfacing tool on said carriage settable into operative position relative to a record on said support; means for moving said carriage across said support; and power-operated means, effective without prior adjustment of the tool relative to the record and controlled by said carriage, for automatically setting said tool into operative position.

3. In a phonograph record resurfacing machine having a support for a record to be resurfaced and a carriage movable along said support: the combination of a resurfacing tool on said car-

- riage having a fully released position and movable therefrom into operative relationship with the record; tool-setting means comprising resilient means for yieldably moving said tool in one 5 operation from said fully released position into said operative relationship with the record; driving means for said carriage; and means for causing operation of said tool-setting means by said driving means.
10. 4. In a phonograph record resurfacing machine having a support for a record and a carriage movable along said support: the combination of a resurfacing tool on said carriage movable towards and away from the record; tool-setting means for moving said tool towards the record into operative position relative thereto, said means comprising means adapted to coact with the record to determine said operative position of the tool; and power means, controlled by 15 said tool-carriage, for operating said tool-setting means.
5. In a phonograph record resurfacing machine having a rotatable record support and a carriage: the combination of record-resurfacing 20 means mounted on said carriage and settable into operative position relative to a record on said support; power means placeable in operation to cause said record-resurfacing means to be set into operative position; and means, operated by said power means and automatically rendered effective subsequent to the completion of the setting of said resurfacing means, for starting both a rotation of said record support and a record resurfacing movement of said carriage.
25. 6. The structure as claimed in claim 5, further including means, fully controlled by said carriage at the completion of its record-resurfacing movement, for moving said record-resurfacing means out of set position and for stopping said power means.
30. 7. In a phonograph record resurfacing machine having a record support: the combination of a carriage having record-resurfacing means mounted thereon; power operated driving means placeable into operation to cause said carriage to be reciprocated along said support; and means, fully controlled by said carriage at the completion of a single cycle in its reciprocative movement, for placing said driving means out of 35 operation.
35. 8. In a phonograph record resurfacing machine having a record support and a resurfacing tool settable into operative position relative to a record on said support: the combination of a carriage for said resurfacing tool; driving means for reciprocating said carriage along said support; means, controlled by said carriage at the completion of the first half cycle in its reciprocative movement, for setting said tool into operative position; and means, controlled by said carriage at the completion of a single cycle in its reciprocative movement, for moving said tool out of operative position and stopping said driving means.
40. 9. In a phonograph record resurfacing machine having a record support and a resurfacing tool settable into operative position relative to a record on said support: the combination of a carriage for said tool; reversible driving means for feeding said carriage back and forth relative to said support; tool-setting means; reversing means for said driving means; and means, controlled by said carriage, for operating said tool-setting means and reversing means in the sequence here named.
45. 10. In a phonograph record resurfacing ma-

chine having a rotatable record support; a tool-carriage: the combination of a reversible driving means for reciprocating said tool-carriage along said support; and one-way action means rotatably coupling said driving means with said record support to cause rotation of said support only during one half cycle of each tool-carriage reciprocation.

11. In a phonograph record resurfacing machine having a record support: the combination of a tool carriage; driving means for reciprocating said carriage along said support; and power operated means, controlled by said carriage, for causing a pause in the carriage movement at the completion of the first half cycle of each carriage reciprocation.

12. In a phonograph record resurfacing machine having a record support and a carriage resurfacing means on said carriage settable into operative position relative to a record on said support: the combination of driving means for reciprocating said carriage relative to said support; means for causing a pause in the movement of the carriage at the completion of the first half cycle of each carriage reciprocation; and means, controlled in predetermined relation to said last-mentioned means, for setting said resurfacing means into operative position within the time interval of said pause.

13. In a phonograph record resurfacing machine having a record support: the combination of a tool-carriage movable back and forth along said support; feeding means for said carriage normally operatively connected therewith; means, rendered operative when said carriage is fed into the end portion of its travel, for rendering said carriage disconnected from its feeding means for a predetermined time interval; and means, responsive to said last mentioned means subsequent to said time interval, for reversing said feeding means to cause a return feed of said carriage.

14. In a phonograph record resurfacing machine having a record support and a carriage and a resurfacing tool on said carriage settable into operative position relative to a record on said support: the combination of reversible driving means for feeding said carriage back and forth relative to said support; means, controlled by said carriage, for rendering said driving means inoperative to feed the carriage and for setting said tool into operative position; and means, operated by said driving means subsequent to the setting of said tool, for rendering said driving means operative to feed the carriage and for reversing the same.

15. The structure as claimed in claim 14, further including means operatively connecting said driving means with said record support for causing rotation of said support during the half cycle of carriage reciprocation subsequent to said pause.

16. In a phonograph record resurfacing machine having a record support and a tool-carriage: the combination of reciprocating means normally operatively connected with said tool-carriage for advancing and returning the tool-carriage along said record support; cam means moved in one direction by said reciprocating means at the completion of the advance of the tool-carriage and returned in the other direction during the initial return of the tool-carriage; means operated by said cam means in its movement in said one direction, for temporarily disconnecting said reciprocating means from said tool-carriage; and means,

- associated with said cam means, for rendering said cam means ineffective to disconnect said reciprocating means from said tool-carriage during the return of said cam means in said other direction. 5
17. In a phonograph record resurfacing machine having a record support: the combination of a tool-carriage; driving means for feeding said tool-carriage along said record support in and against a direction of normal record-resurfacing movement; manipulatable means for controlling the direction of feed of said carriage; and means, associated with said tool-carriage, for preventing manual operation of said manipulatable means while the carriage is progressing through its record-resurfacing movement. 10
18. In a phonograph record resurfacing machine having a record support: the combination of a tool-carriage; driving means placeable into operation to produce one cycle of reciprocative movement of said tool-carriage across said support; manipulative means for rendering said driving means operative to produce the cycle of carriage movement; and means, controlled by said carriage, for rendering said manipulative means inaccessible for operation while said carriage is progressing through the major part of its cycle of movement. 15
19. In a phonograph record resurfacing machine having a record support: the combination of a tool-carriage; driving means for feeding said tool carriage along said record support from and towards a start position; manipulatable means for controlling said driving means; and means associated with said tool-carriage, for rendering said manipulative means ineffective while the carriage is out of start position. 20
20. In a phonograph record resurfacing machine having a rotatable record support, a brake for restraining said record support against rotation and a tool-carriage: the combination of driving means for reciprocating said tool-carriage across said support; and means, operated by said driving means at the completion of one half cycle of each carriage reciprocation, for rendering said brake inoperative and subsequently causing said record support to be set into rotation. 25
21. The structure as claimed in claim 20, further including means, responsive to the terminal movement of the carriage at the completion of each cycle of its reciprocation, for rendering said brake operative and coordinately rendering said driving means inoperative. 30
22. In a phonograph record resurfacing machine having a rotatable record support: the combination of a tool-carriage; driving means for rotating said record support and concurrently imparting a record-resurfacing movement to said tool-carriage; and means, controlled by said tool-carriage, for braking the rotation of said support and coordinately stopping said driving means at the completion of the record-resurfacing movement of said carriage. 35
23. In a phonograph record resurfacing machine having a rotatable record support, a tool-carriage and driving means for rotating said record support and concurrently imparting a record-resurfacing movement to said tool-carriage: the combination of means, operated incidental to the completion of the record-resurfacing movement of said tool-carriage, for braking the rotation of said record support; and means, operated by said braking means, for stopping said driving means. 40
24. In a phonograph record resurfacing ma-
- chine having a record support and means for rotating said support: the combination of control means for said rotating means; means for braking the rotation of said support; and spring means for operating said braking means and coordinately operating said control means to render said rotating means inoperative. 5
25. In a phonograph record resurfacing machine having a rotatable record support and a brake for retarding the rotation of said support: the combination of a tool-carriage; driving means for reciprocating said tool-carriage across said record support; means, operated at the completion of the first half cycle of each tool-carriage reciprocation, for rendering said brake inoperative and for causing said record support to be coupled with said driving means to place said support in rotation; and means, responsive to the movement of the tool-carriage at the completion of each reciprocation thereof, for rendering said brake operative and said driving means inoperative. 10
26. The structure as claimed in claim 25, further including manipulative means, operable at the completion of one cycle of tool-carriage reciprocation, for restarting said driving means to cause said tool-carriage to be moved through another cycle of its reciprocative movement. 15
27. In a phonograph record resurfacing machine having a rotatable record support, braking means for said support and a resurfacing tool settable into operative position relative to a record on said support: the combination of driving means reversible to feed said carriage back and forth along said support; means controlled by said carriage in response to a feeding movement of the carriage in one of its movable directions, for setting said tool into operative position, rendering said braking means inoperative, and reversing said driving means to feed the carriage in the other of its movable directions; and means, rendered effective upon the reversal of said driving means, for causing rotation of said record support during the feeding of said carriage in said other direction. 20
28. In a phonograph record resurfacing machine having a record support and a tool-carriage: the combination of feeding means for advancing said tool-carriage along said support comprising a motor having a main circuit; means selectively operable to reverse the direction of rotation of said motor to cause a return of said tool-carriage; and means, included in said circuit as an incident to the reversal of said motor, for controlling the rate of the return of said tool-carriage. 25
29. In a phonograph record resurfacing machine having a record support and a tool-carriage: the combination of feeding means for advancing said tool-carriage along said support comprising a motor having a main circuit; means selectively operable to reverse the direction of rotation of said motor to cause a return feed of said tool-carriage; and switch means, included in said circuit as an incident to the reversal of said motor, for stopping the return feed of said tool-carriage. 30
30. In a phonograph record resurfacing machine having a record support and a tool-carriage: the combination of feeding means for advancing said tool-carriage along said support comprising a motor having a field and an armature; a main circuit for supplying power to said motor; a reversing circuit connectable into said main circuit to reverse the polarity of said field. 35

with respect to said armature so as to reverse the direction of feed of said tool-carriage; and switch means in said reversing circuit, operated incidental to the reverse feed of said tool-carriage, for stopping said feeding means.

31. In a phonograph record resurfacing machine having a record support and a tool-carriage: the combination of feeding means for advancing said tool-carriage along said support comprising a motor having a field and an armature; a main circuit for supplying power to said motor; a reversing circuit, automatically connected into said main circuit by the advance of said tool-carriage, for reversing the polarity of said field with respect to said armature so as to reverse the direction of feed of said tool-carriage; and switch means in said reversing circuit, operated incidental to the reverse feed of said tool-carriage, for opening said reversing circuit to stop said feeding means.

32. In a phonograph record resurfacing machine having a movable tool-carriage: the combination of feeding means for said tool-carriage normally operatively connected therewith; means for disconnecting said tool-carriage from said feeding means; and means, rendered effective

upon the disconnection of said tool-carriage from said feeding means, for locking the tool-carriage.

33. In a phonograph record resurfacing machine having a rotatable mandrel for supporting a record to be resurfaced; and an endgate for said mandrel: the combination of a latch for said endgate; driving means for the machine placeable into operative and inoperative conditions; and means, controlled by said latch, for placing said driving means into operative condition.

34. In a phonograph record resurfacing machine: the combination of a rotatable support for a record to be resurfaced; a resurfacing tool settable into operative position relative to a record on said support; a carriage for said tool movable in a direction operative to cause a resurfacing of a record on said support by said tool; power means placeable into operation to set said tool and to subsequently rotate said record support and impart a record resurfacing movement to said carriage; and means, operated as an incident to the completion of a mounting of a record on the machine, for placing said power means into operation to cause a resurfacing of the mounted record.

RICHARD M. SOMERS.

CERTIFICATE OF CORRECTION.

Patent No. 2,209,835.

July 30, 1940.

RICHARD M. SOMERS.

It is hereby certified that error appears in the printed specification of the above numbered patent requiring correction as follows: Page 9, first column, line 60, for "enagement" read --engagement--; line 73, for "initial" read --initial--; and second column, line 19, for "is" read --it--; line 22, for "at at" read --as at--; page 12, second column, line 1, claim 10, for "support;" read --support and--; line 19, claim 12, before "resurfacing" insert --and--; page 14, first column, line 5, claim 30, for "mans" read --means--; line 25, claim 32, for "disconnetcng" read --disconnecting--; and that the said Letters Patent should be read with this correction there-in that the same may conform to the record of the case in the Patent Office.

Signed and sealed this 12th day of November, A. D. 1940.

Henry Van Arsdale,
Acting Commissioner of Patents.
